UNITED STATES PATENT OFFICE

147,612

DESIGN FOR AN AUTOMOBILE BUMPER GUARD

Robert Cadwallader, Detroit, Mich., assignor to
Chrysler Corporation, Highland Park, Mich., a
corporation of Delaware

Application December 29, 1945, Serial No. 125,124

Term of patent 7 years

(Cl. D14—6)

To all whom it may concern:

Be it known that I, Robert Cadwallader, a citizen of the United States, residing in the city of Detroit, county of Wayne, and State of Michigan, have invented a new, original, and ornamental Design for an Automobile Bumper Guard, of which the following is a specification, reference being had to the accompanying drawing, forming part thereof, in which:

Fig. 1 is a front elevational view of the automobile bumper guard showing my new design;

Fig. 2 is a side elevational view of the same looking at the right side of Fig. 1;

Fig. 3 is a side elevational view thereof looking at the left side of Fig. 1; and

Fig. 4 is a top plan view of the automobile bumper guard.

The characteristic features of my design are shown in the full lines in the drawing.

I claim:

The ornamental design for an automobile bumper guard, substantially as shown and described.

ROBERT CADWALLADER.
